(57)

CLAIM

The ornamental design for a mosquito netting for stroller, as shown and described.

DESCRIPTION

FIG. 1 is a front, left, and top perspective view of a mosquito netting for stroller, showing my design.

FIG. 2 is a rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a cord; and,

FIG. 10 is a partial enlarged view of an area labeled 10 in FIG. 2 comprising a cord lock.

(Continued)

The broken lines shown in the drawings are included for the purpose of illustrating portions of the mosquito netting for stroller that form no part of the claimed design.
